UNITED STATES PATENT OFFICE.

CHARLES DAHLSTROM, OF JAMESTOWN, NEW YORK.

METALLIC DOOR.

SPECIFICATION forming part of Letters Patent No. 747,149, dated December 15, 1903.

Application filed January 7, 1903. Serial No. 138,134. (No model.)

To all whom it may concern:

Be it known that I, CHARLES DAHLSTROM, a citizen of the United States, residing at Jamestown, in the county of Chautauqua and State of New York, have invented certain new and useful Improvements in Metallic Doors, of which the following is a specification.

My invention relates to metallic doors; and the object thereof is to provide a comparatively inexpensive and exceedingly light but durable and rigid door which is air-tight and weatherproof.

Another object is to devise a door of this character which can be made ornamental, which is seamless on one side and in appearance can be made to resemble any of the common styles of panel-doors, and which, owing to its peculiar construction, is fireproof and sound-proof.

Another object is to so construct my improved door that the large dies heretofore used in shaping the metal sheets for this purpose are dispensed with and the sheets rolled into the proper shape with less power and greater facility, and consequently with less time and expense.

Other objects will be apparent from the detail description of the invention which will be presently given.

The invention consists of the new and novel construction of a door formed of sheet metal and having an invisible seam or seams and which is constructed of two thicknesses of metal providing stiles, panels, and rails to resemble as near as may be any common panel-door constructed of wood.

This invention is susceptible to many changes in form, size, and connection of metal sheets or place of connection of the same, as I do not wish to confine myself to the exact construction and arrangement herein described, and shown in the accompanying drawings, but hold myself at liberty to make such changes as fairly lie within the scope of my invention.

Referring to the drawings, Figure 1 is a side elevation of a door embodying my invention. Fig. 2 is a top view of the same. Fig. 3 is a broken vertical section, on an enlarged scale, taken on line $v v$, Fig. 1. Fig.

4 is a vertical section taken on line $w w$, Fig. 5. Fig. 5 is a horizontal section taken on line $x x$, Fig. 4. Fig. 6 is an enlarged horizontal section taken on line $y y$, Fig. 1. Fig. 7 is an enlarged horizontal section taken on line $z z$, Fig. 1. Figs. 8, 9, 10, and 11 are horizontal sections taken through the panels of doors, showing modified forms of my invention.

Referring to the drawings in detail, like numerals of reference refer to like parts in the several figures.

My improved door is formed in its preferred construction of two metal sheets 1 and 2, both extending the full length of the door. The sheet 1 is provided centrally with a panel depression or formation 3, arranged to extend the full length thereof and having its defining-walls 4 ornamenteally formed to represent a molding. On opposite sides of the said panel depression or formation the sheet is bent at right angles to form the side edges 5 of the door. It is then bent inwardly or recurved, as at 6, to form the hollow stiles 7 and is next arranged to form receding defining-walls 8, which represent moldings similar to those formed by the defining-walls 4 on the opposite side of the door, the edges of the sheet finally recurring or terminating in lips 9, extending into the hollow stiles to form channels to interlock with the edges of the metal sheet 2, as will be presently described. The metal sheet 2 co-operates with the depressed panel portion 3 of the sheet 1 to form the complete panel. The sheet 2 is of a width somewhat greater than the panel depression 3 and has its edges recurved, as at 10, to form channels, which receive the lips 9 of the sheet 1, thus forming vertical seams in the stile, which are invisible from the outside, and providing a door having the appearance of being formed of seamless sheet metal. By means of this construction the panel depression 3 and ornamental defining-walls 4 and 8, as well as the stiles, can be rolled into the desired outline with ease and great facility and the sheet 2 conveniently connected thereto, the whole forming an air-tight double sheet-metal door through which neither smoke nor hot air can pass, as the one side thereof is

100

formed in one integral piece without seam or crevice of any kind.

Between the metal sheet 2 and the depressed panel portion of the sheet 1 a filling-sheet 11 of asbestos or any other material of like nature is interposed, and in the hollow stiles ground asbestos or any other suitable material may be inserted to make the door absolutely fireproof and sound-proof. This filling need not necessarily be of a non-combustible nature, as other material combustible in the open air, but non-combustible in an air-tight inclosure, has by experiment been found more satisfactory, as it is not so liable to act upon the steel and cause corrosion. When a sound-proof door only is desired, any other suitable material may be used as a filling.

The edge of the door to which the hinges are secured is provided with apertures 12, and the inner face thereof is provided with a reinforcing-strip 13, secured thereto in any practicable manner. This greatly strengthens and stiffens the door at this otherwise weak point and permits the hinges 14 to be secured to the reinforcing-strip and brought flush with the edge of the door.

If desired, the panel may be provided with moldings 15 to further ornament the same, and when used they are preferably riveted to the door, each rivet passing through both moldings and the metal sheets 1 and 2. These moldings tie the two sheets together and prevent vibration of the same, particularly on wide doors.

The upper and lower rails 16 17, respectively, are each formed of a single sheet of metal bent upon itself to form a channeled member, having its sides 18 separated to correspond with the thickness of the stiles, and thus present an even surface therewith. The horizontal portions 19 of the rails are provided with extensions 20 21, which bear against the open upper and lower ends of the stiles, respectively. The sides of these rails are of a length to snugly fit between the stiles, and the upper ends are made to recede and form the upper and lower ornamental defining-walls 22 23, respectively, of the panel. These defining-walls terminate in recurved lips 24, separated by a space 25, corresponding to the thickness of the panel, thus providing a suitable bearing for the rails against said panel. At regular intervals separators 26 are provided between the side walls and the recurved lips of the rails, and passing through said separators, the sides and recurved lips of the rails, and the panel are rivets 27, which securely tie the parts together and greatly stiffen the door at this point.

The upper and lower ornamental defining-walls of the panel are fitted to the side defining-walls 4 and 8, and the recurved lips of the rails 16 17 are somewhat shorter than the sides thereof, so as to fit the narrowest space be-

tween the side defining-walls to permit of bearing firmly against the panel.

The hollow rails are also filled with ground asbestos or other suitable material. If desired, the rails may be brazed, welded, or otherwise secured to the metal sheets 1 and 2, forming the body of the door, and the rivets dispensed with; but I find the riveting of the parts, in addition to welding the abutting edges, to be the most satisfactory.

The defining-walls of the panel by being offset and curved greatly stiffen the door and permits the use of a much lighter grade of metal without effecting the rigidity of the door, which would otherwise be impossible. Any desired number of moldings or intermediate rails may be secured to the panel to produce any desired design; but such is not necessary in a door of this type, as it would unnecessarily increase its weight.

In the modification shown in Fig. 8 the stiles and panel of the door or, in other words, the body of the door is also formed of two sheets of metal 28 29, each sheet forming a stile 30 and one side of the panel 31. One edge of each sheet is recurved to form a channel and terminates in a lip 32 at the inner edge of the stile forming part thereof, and the other end thereof terminates in a recurved portion forming a channel 33, in which the adjacent lip of the connecting-sheet is secured.

In the modification shown in Fig. 9 the stiles and panel forming the body of the door are formed of a single sheet of metal arranged to have one edge thereof recurved to form a channel and terminate in a lip 34 at the inner edge of one stile to extend into the same and its other edge recurved to form a channel 35 at the junction of the panel with said stile, the said lip being secured in the channel 35 to form a seam invisible from the outside of the door.

In the modification shown in Fig. 10 the panel and stiles forming the body of the door are formed of two sheets of metal. The edges 36 of the panel portion 36 on one side of the door is doubled upon itself, as at 37, and then recurved, as at 38, and carried laterally and directed to form the stiles, which are provided at their inner edges with a channeled portion 39, formed at the edges of the sheet, said channeled portion receiving the doubled portions 37 of the panel portion 36 and also the edges of the panel portion 40, forming the other side of the panel, thus securely holding the two sides of the panel together.

In the modification shown in Fig. 11 the stiles and panel are also formed of two sheets of metal. The stiles and one side of the panel are constructed of one sheet and the other side of the panel is formed of the other sheet. The edges of one panel portion 41 are recurved, as at 42, to form channels and then carried laterally and outwardly to form the ornamental defining-wall 43 of the panel and

finally directed to form the hollow stiles. The edges of the sheet terminate in channels 44 of a size sufficiently large to receive the channeled edges of the panel portion 41. The 5 metal sheet forming the opposite panel portion 45 has its edges secured in the channeled edges of the panel portion 41.

By preference a sheet of asbestos or other suitable material is interposed between the 10 two panel portions in each modified construction.

Having thus described my invention, what I claim is—

1. A door formed of sheet metal and having 15 one sheet provided with a panel formation serving as one side of the panel and having its sides recurved to form the stiles of the door and its edges oppositely recurved to form channels, and another sheet forming the other 20 side of the panel and having its edges recurved to interlock with the recurved edges of the first-mentioned sheet.

2. A door formed of sheet metal and having one sheet provided with a panel formation 25 serving as one side of the panel and being recurved on opposite sides of the panel formation to form the stiles of the door, and another sheet forming the other side of the panel and having its side edges connected 30 with the side edges of the first-mentioned sheet.

3. A door formed of sheet metal and having one sheet provided with a panel formation 35 serving as one side of the panel and being recurved on opposite sides of said panel formation to form the stiles of the door, a second sheet forming the other side of the panel and having its side edges connected with the side 40 edges of the first-mentioned sheet, and a third and forth sheet forming the upper and lower rails of the door, respectively, said last-mentioned sheets being doubled upon themselves to form channeled rails into which the upper and lower ends of the panel are 45 fitted.

4. A door formed of sheet metal having a panel, and stiles bounding the sides of the panel, the edges of the metal sheets forming 50 said panel and stiles being connected at the junction of the two, and end rails each formed of a separate sheet of metal bent upon itself to form a channeled rail into which the ends of the first-mentioned metal sheets are fitted, said last-mentioned sheets forming the end 55 rails bounding the upper and lower ends of the panel.

5. A door formed of sheet metal having a panel, and stiles bounding the sides of said panel, the edges of the metal sheets forming 60 said panel and stiles being connected at the junction of the two, end rails each formed of a separate metal sheet bent upon itself to form a channel and having the edges of the sheet recurved parallel with the sides of the 65 channel between which the panel is fitted, separators between the side walls of the chan-

neled rails and the recurved edges thereof, and rivets passing through the rails, separators and the panel to securely fix the rails to the latter.

6. A door formed of sheet metal and having its side walls connected by an edge wall, and a reinforcing-strip secured to the inner face of the edge wall, said edge wall being provided with an aperture to permit the door-hinge to be secured to said reinforcing-strip. 75

7. A door formed of sheet metal bent upon itself to form edge walls and having its side walls separated, and a reinforcing-strip secured to the inner face of the edge wall, the 80 latter having a perforation exposing said reinforcing-strip to permit the door-hinge to be secured thereto.

8. A door formed of sheet metal bent upon itself to form hollow stiles and panel formations on opposite sides of the door, said panel formations being separated slightly and at least one of said panel formations being formed integrally with the stiles, and a filling sheet or lining interposed between said 90 panel formations.

9. A door formed of sheet metal comprising one sheet forming the stiles and one side of the panel, a second sheet serving as the other side of the panel and having connection with 95 the first-mentioned sheet by a vertical seam at the junction of the stiles to said panel, and a sheet of asbestos interposed between the two walls of the panel.

10. A double sheet-metal panel-door having 100 its stiles and one side of the panel made seamless and having an invisible interlocking seam at the junction of one stile with the other side of the panel.

11. A double sheet-metal panel-door having 105 hollow stiles and the edges of the metal sheet or sheets forming the door, provided with channeled edges interlocked on the inside of the hollow stile or stiles.

12. A double sheet-metal door having the 110 edges of the metal sheet or sheets forming the same connected by an invisible interlocking seam.

13. A door formed of sheet metal and having one sheet arranged to form one side, the 115 edges, and a portion of the other side of the door, and a second sheet forming the remaining portion of the last-mentioned side of the door, both sheets having interlocking channeled or recurved edges. 120

14. A double sheet-metal door having two sheets of metal forming a panel and stiles on opposite sides of the panel, said sheets having interlocking channeled or recurved edges connected at the point of meeting of the stiles 125 with the panel on one side of the door.

15. A double sheet-metal door constructed to form hollow stiles and two opposing panel portions, the door having a vertical seam on one side at the junction of one panel portion 130 with the adjacent hollow stile.

16. A double sheet-metal door comprising

a sheet of metal extending the full length and the full width thereof to form one side and having recurved side marginal portions forming a portion of the other side of the door, and 5 a second metal sheet extending the full length of the door and being secured by means of invisible interlocking seams to the edges of the first-mentioned sheet.

In testimony whereof I have hereunto affixed my signature in the presence of two subscribing witnesses.

CHARLES DAHLSTROM.
